United States Patent

Des. 239,968
Patented May 18, 1976

239,968

HOLDER FOR PATIO TORCH

William V. McNamara, Chicago, Ill., assignor to
Bell Chemical Company

Filed Sept. 23, 1974, Ser. No. 508,555

Term of patent 14 years

Int. Cl. D26—02

U.S. Cl. D48—24 R

FIG. 1

FIG. 2

FIG. 3

FIG. 1 is a front view of a holder for patio torch embodying my new design;

FIG. 2 is a top view thereof;

FIGS. 3 and 4 are respectively right and left views thereof;

FIG. 5 is a rear view thereof; and

FIG. 6 is a bottom view thereof.

I claim:

The ornamental design for holder for patio torch, substantially as shown.
